(57) **CLAIM**

The ornamental design for a dog leash with integrated pouch, as shown and described.

DESCRIPTION

FIG. 1 is a top perspective view of a dog leash with integrated pouch showing my new design in a first configuration with the pouch closed.

FIG. 2 is a top plan view thereof.

FIG. 3 is a bottom plan view thereof.

FIG. 4 is a left side elevation view thereof.

FIG. 5 is a rear elevation view thereof.

FIG. 6 is a front elevation view thereof.

FIG. 7 is an enlarged view of detail “7” identified in FIG. 2, shown for clarity of disclosure.

FIG. 8 is a top plan view of the pouch of FIG. 7, shown for clarity of disclosure.

FIG. 9 is an enlarged view of detail “9” identified in FIG. 1, shown in the first configuration; and,

FIG. 10 is a top perspective view of the pouch of FIG. 9, shown with the pouch closed and expanded in a third configuration, for clarity of disclosure.

The wide-dashed broken lines showing a leash, hardware, and fasteners, depicts portions of the dog leash with integrated pouch that form no part of the claimed design. The tight-dashed broken lines on the surfaces of the pouch depict stitching and forms no part of the claimed design. The long dash-dot-dash broken lines show the boundary of the claim. All broken lines form no part of the claim.
